UNITED STATES PATENT OFFICE.

JOHN PEARSON, OF SOMERSET, WISCONSIN, ASSIGNOR OF ONE-THIRD TO JAMES F. WILLIAMSON AND ONE-SIXTH TO FRANK D. MERCHANT, OF MINNEAPOLIS, MINNESOTA.

LIGHTNING-ARRESTER.

No. 887,221.

Specification of Letters Patent.

Patented May 12, 1908.

Application filed November 24, 1905. Serial No. 288,829.

To all whom it may concern:

Be it known that I, JOHN PEARSON, a citizen of the United States, residing at Somerset, in the county of St. Croix and State of Wisconsin, have invented certain new and useful Improvements in Lightning-Arresters; and I do hereby declare the following to be a full, clear, and exact description of the invention, such as will enable others skilled in the art to which it appertains to make and use the same.

My invention has for its object to provide an improved lightning arrester which will allow a free discharge from a line to the ground, of abnormally high static charges, such as produced by lightning, but which will offer great resistance to the dynamo or line current, and not permit such flow thereof to the ground, as would short circuit the generator and thereby impair the good running condition of the system.

The invention is particularly adapted to increase the efficiency of so-called "horn lightning arresters". Horn lightning arresters are at present in quite extensive use, and their general construction and operation are understood by persons familiar with this subject.

In carrying out my invention, I provide a horn lightning arrester with what I term a "barrier". In the preferred arrangement this barrier is placed between the horns of the arrester, and its bottom at the place where the horns come nearest to each other, is of such character that while the lightning charge will force its way under the same, it will offer a very great resistance to the dynamo arc which follows.

The invention is illustrated in the accompanying drawings, wherein like characters indicate like parts throughout the several views.

Figure 1 is a diagrammatic view, showing a horn lightning arrester having my invention applied thereto, the said arrester being interposed between the ground and one of the line wires, of a three-phase alternating power-transmission system. Fig. 2 is a detail in side elevation, showing one of the so-called "barriers" removed from working position. Fig. 3 is a detail in side elevation, illustrating another form and arrangement of the barrier in respect to the horns of the arrester.

The numeral 1 indicates a three-phase

alternating generator, and the numeral 2 indicates the three line wires of the system of which said generator is a part.

The numeral 3 indicates choke coils interposed in the line wires 2, at the generating end of the line.

The numeral 4 indicates a conductor leading from one of the line wires 2, and having its sections connected to the horns 5, of a horn lightning arrester of the usual or any suitable construction. The horns of this arrester diverge upwardly. In practice there should be a lightning arrester for each line wire, and this arrester should be a free discharger, such as a horn arrester. It may be here stated, however, that this invention is not limited to use in connection with poly-phase generating systems, but may be used in connection with power-transmission lines or electrical conducting systems of various character. However, this type of arrester works to the best advantage in connection with high tension power-transmission circuits.

The barrier which is provided in accordance with my invention is preferably in the form of a thin plate 6 which, as illustrated, in the drawings, may be assumed to be a sheet of mica, having, as shown, near its lower portion, one or more small perforations 7. This barrier is interposed between the horns of the arrester, with its perforation or perforations 7 in line, or approximately in line, with the most closely positioned portions of the two horns of said arrester. This barrier may be held in the position stated, by a slit supporting pin 8, or by any other suitable form of holder.

With the barrier interposed between the horns of the arrester, as shown in Fig. 1, a lightning charge from the line being of enormously high voltage and of very small quantity or amperage will force its way through the perforations 7 of said barrier; while with the arrangement shown in Fig. 3, the lightning charge will force its way from one horn to the other of the arrester under the barrier. Otherwise stated, the said barrier offers resistance to the passage of the dynamo arc or current on account of thermal and electro-dynamic action so that it flashes upward or around the barrier, generating great heat and causing the heated gases to rush upward and to carry or force the dynamo arc up to the upper ends of the horns of

the arrester, where the resistance through the air, from the one horn to the other, becomes so great that the arc goes out. Furthermore, the said barrier causes the metallic fumes which are burned by the arc, from the prongs of the arrester, to pass upward or around said barrier, and hence prevents the formation of the partial conductor directly between the most closely positioned portions 10 of the said horns. Many materials other than mica have the properties above indicated.

A barrier of paper will allow lightning to flash through it, and forces the dynamo current upward; but of course when a paper barrier is employed, it must be replaced each time after such a charge has been grounded, as such paper will usually be burned up.

A very good barrier may be made of a thin 20 piece of asbestos. When this form of barrier is employed, the lightning may be made to pass through it, and after the lightning has passed through it, the dynamo arc will be forced upward, on account of the thermo- 25 dynamic and electro-dynamic action and the great resistance of the asbestos.

A mica barrier, for instance, may be used without perforations or holes if the barrier be set with its lower edge very slightly below 30 the lowermost and most closely spaced portions of the horns of the arrester. Such an arrangement is illustrated in Fig. 3, wherein the numeral 5^a indicates the horns of the lightning arrester, and 6^b indicates the barrier, shown as supported by a pin 8^a, with its lowermost edge 6^c slightly below the most nearly approaching point 5^b of the said horns.

When a static discharge occurs at the 40 points 5^b on the horn arrester shown in Fig. 3, the dynamo current establishes an arc at this point and this arc is forced to travel upward on account of the thermal and electro-dynamic actions of the barrier 6^b. At such time the barrier 6^b interposed between the 45 horns 5^a increases the thermal action by increasing the length of the arc, and the said barrier also increases the resistance of the arc by making it longer and longer as the arc is forced upward. The arc continues to travel 50 around the lower part of the barrier 6^b until the fumes become so dense on either side of the barrier that the current can travel up on both sides and complete a circuit across the top of the barrier. The arc keeps on going 55 higher and higher until the horn is diverted so much that the arc must go out. With such arrangement, the lightning will flash around or under the lower edge of the barrier, but when the dynamo arc tries to maintain 60 itself around the bottom of such barrier, it generates such intense heat that the rising gases force the arc upward, and cause the

same to be disrupted, or to go out, at the upper portions of the arrester horns.

A mica barrier without perforations could 65 be coated with a conducting paint 6^a of high resistance, but of enough surface to allow electric currents of abnormally high frequency to pass around its surface freely.

A very thin plate of platinum on both 70 sides of a sheet of mica, but not extending as low as the lower portion of the mica would afford an efficient barrier. It would not impede the free discharge of the lightning to the ground, and would prevent the direct 75 contact of the metallic fumes burned from the horns of the arrester on the passage sides of said barrier.

The expression "non-conductor" is used in a liberal sense, to include materials generally known as "non-conductors" of electricity and which will serve as insulations therefor. The expression "non-fusible" is used to include such materials as will not be reduced to molten or gaseous condition by 85 an ordinary lightning discharge.

From what has been said, it will be understood that the barrier may be constructed from a great many different kinds of material, and may be arranged in a great many 90 different ways. The essential features of the invention are thought to have been made clear from the foregoing description and statements made.

What I claim is:

1. In a lightning arrester having diverging horns of conducting material, a barrier interposed between said horns, substantially as described.
2. In a lightning arrester having diverging horns of conducting material, a non-fusible barrier interposed in the air gap between said horns, substantially as described.
3. In a lightning arrester having upwardly diverging horns of conducting material, a barrier interposed between the horns thereof with its lower edge approximately in horizontal line with the most nearly approaching portions of said horns, substantially as described.
4. In a lightning arrester having upwardly diverging horns of conducting material, a barrier constructed of non-fusible material interposed between said horns with its lowermost edge approximately in horizontal line 105 with the most nearly approaching portions of said horns, substantially as described.

In testimony whereof I affix my signature in presence of two witnesses.

JOHN PEARSON.
